(57) **CLAIM**

The ornamental design for an electric vehicle charging station, as shown and described.

DESCRIPTION

FIG. 1 shows a perspective view of an electric vehicle charging station;

FIG. 2 shows a front view of the electric vehicle charging station of FIG. 1;

FIG. 3 shows a back view of the electric vehicle charging station of FIG. 1;

FIG. 4 shows a right view of the electric vehicle charging station of FIG. 1;

FIG. 5 shows a left view of the electric vehicle charging station of FIG. 1;

FIG. 6 shows a top view of the electric vehicle charging station of FIG. 1; and,

FIG. 7 shows a bottom view of the electric vehicle charging station of FIG. 1.
